UNITED STATES PATENT OFFICE.

JOHN HEGGEN, OF SEATTLE, WASHINGTON.

PLANER AND CUTTER HEAD.

1,305,650.

Specification of Letters Patent.

Patented June 3, 1919.

Application filed June 25, 1917. Serial No. 176,895.

To all whom it may concern:

Be it known that I, JOHN HEGGEN, a citizen of the United States, residing at Seattle, in the county of King and State of Washington, have invented a new and useful Improvement in Planer and Cutter Heads, of which the following is a specification.

This invention relates to improvements in planer and cutter heads and more particularly to improvements in means for securing the knives or blades in such heads, and the object of this improvement is to provide means whereby blades of various shapes and forms for performing different classes of work may quickly and easily be inserted in and removed from a cutter or planer head, thus making it possible to perform various different kinds of work without changing the head.

20 In carrying out this object blade holding jigs of substantially uniform external shape are provided and the planer or cutter heads are recessed for the reception of these jigs, so that one set of jigs may be easily and quickly 25 removed and another set inserted, the several jigs being suitably constructed for the reception of knives of various shape and form.

The jigs are slotted in various ways for the reception of the knives and all of such 30 jigs are adapted to clamp the knives tightly when stud bolts that are provided therein are expanded or screwed outwardly against the walls of the recesses in the cutter heads.

The chip breaks are constructed integral 35 with the jigs so that when such chip breaks become worn new jigs having new chip breaks thereon may be substituted at a relatively small cost.

The invention consists in the novel construction, adaptation and combination of 40 blade clamping jigs and cutter heads, as will be more clearly hereinafter described and claimed.

In the drawings Figure 1 is a view in end 45 elevation of a planer head constructed in accordance with this invention; Fig. 2 is a view in side elevation of the same, the lower portion thereof being broken away; Fig. 3 is a detached view in elevation of a blade 50 holding jig that may be inserted in the planer head; Fig. 4 is a view in perspective of one element of the jig shown in Fig. 3; Fig. 5 is a view in elevation of a clamping 55 jig for a planer head, certain parts being broken away; Fig. 6 is a view in sectional perspective of the jig shown in Fig. 5; Fig. 7

is a view in elevation of a modified form of clamping jig for a planer head; Fig. 8 is a view in cross section on broken line 8, 8 of Fig. 7; Fig. 9 is a view in end elevation of a cutter or matcher head embodying this invention, a portion thereof being broken away; Fig. 10 is a view in side elevation of the head shown in Fig. 9 and Figs. 11, 12, 13, 14, 15 and 16 are views in perspective of various forms of knives that may be used in the cutter or matcher head.

Referring to the drawings throughout which like reference numerals indicate like parts, the numeral 1 indicates a cylindrically formed planer head that is provided with longitudinally extending peripheral recesses 2 for the reception of blade clamping jigs 3.

The recesses 2 have rear walls 4 that are 75 inclined forwardly and front walls 5 that are inclined slightly to the rear and are slotted lengthwise as at 6 for the reception of the heads of stud bolts 7 by the use of which the jigs are securely clamped in the 80 heads and the blades are clamped in the jigs.

The stud bolts are screwed into the front side of the jigs and the jigs are slotted as at 8 for the reception of cutters or blades 9 of the form more clearly shown in Figs. 5 and 85 6, there being left a relatively thin wall of metal 10 at the bottom of the slot 8 that admits of a slight flexing so that the blades may be easily inserted into the slots and will be securely clamped therein when the stud 90 bolts are expanded or screwed outwardly against the wall of the recess 2 in the head in which the jig is inserted.

The slots 8 are preferably cut entirely 95 through the jig at the ends thereof as indicated at 11, Fig. 5, and the ends of the blades are provided with elements 12 that project downwardly into such slots on each side of the wall portion 10 to prevent the blade from moving endwise in the jig before it is 100 clamped therein by the tightening of the stud bolts 7.

The jigs are inserted by sliding them into the recesses from one end thereof and the heads of the stud bolts are rounded so that 105 they will fit snugly within the slots 6 when the stud bolts are screwed outwardly to clamp the jigs.

The top edge of the front portion of the jig 3 forms the chip break as indicated at 50 110 so that when such chip break becomes worn it may be renewed by substituting a new jig.

This is a marked advantage over certain forms of heads whereon the chip break is a part of the head itself.

Figs. 7 and 8 illustrate a modified form of 5 jig wherein the knife receiving slot 8 extends entirely through the jig for the greater part of its length and the portions of the jig on opposite sides of the slot are secured together by small integral metal sections or 10 bridges 13 that flex to admit a blade to be clamped in the slots.

14 are screws that extend crosswise of the slot 8 just above the sections 13, see Fig. 8, to prevent the two parts of the jig on opposite 15 sides of the slot from being spread apart and the jigs broken.

The knife 15 that fits within this form of 20 jig is recessed as at 16 to fit over the screws 14 and metal bridge sections 13 and may be held in adjusted position within the jig before the latter is inserted in the head by 25 tightening up the screws 14.

Figs. 3 and 4 illustrate a jig composed of 30 three separate sections 17, 18 and 19 that are joined together by a rod 20 that passes through each of such sections lengthwise thereof.

The several sections 17, 18 and 19 are each slotted at the ends thereof for the reception 35 of knives 21 and are further provided with slots 22 that extend lengthwise thereof from the knife receiving slots to a point near the opposite end of the jig section so that when the stud screws in the front of the jig sections are screwed outwardly against a solid 40 wall the knives 21 will be securely clamped in the jig sections.

The combination of knives shown in Fig. 45 3 are the ones commonly used in finishing ceiling lumber but it is obvious that many other combinations of knives may be set up in this same manner.

The jigs shown in Figs. 3 and 4 and in Figs. 11 to 16 inclusive are each provided 50 with integral toe pieces 23 that do not interfere with the operation of the stud bolts and give the bottoms of the jigs a bearing on the entire bottoms of the recesses, 2.

Fig. 9 illustrates this invention as applied 55 to a cutter head or matcher head which consists of a cylindrical disk 25 recessed as at 26 for the reception of blade holding jigs 27, the disk 25 being relatively narrow and being adapted to be mounted for rotation in a vertical plane and the jigs 27 being of a suitable length to fit within the recesses in the disk 25.

The blade receiving slots 28 in the jigs 27 do not extend entirely therethrough but 60 leave a relatively thin wall of metal between the bottom of the slot and the bottom of the jig which flexes and permits the blade to be securely clamped as the stud bolts are screwed outwardly against the walls of the 65 recesses in the head.

Fig. 12 illustrates the top edges of a jig 27 recessed as at 28' to facilitate the removal and insertion of blades.

29 are screws that are inserted in one end of each jig 27 in such manner that the head of the screw will overhang the bottom side of the jig and thereby be caused to engage with the face of the cutter head and serve as a stop for the jig when it is inserted in the head. 75

Fig. 13 shows a form of knife and jig 30 that may be used for finishing the edge of ship lap lumber. This jig is substantially the same as the jig 27 except that the top edge thereof is cut away for about half its 80 length, as indicated at 31.

Fig. 14 illustrates a jig 32 and blade 33 for forming the tongue on flooring the top edge of the jig being recessed as at 34 and the knife being recessed as at 35. 85

Fig. 15 illustrates a jig 36 recessed on one end as at 37 for holding a groove cutting knife 38. The edges of the knife 38 are beveled to fit the beveled sides of the recess 37 as indicated at 39 so that the knife will not easily slip out of the recess and the jig is provided with a slot that extends from the recess 37 to a point near the opposite end of the jig so that when the jig is clamped in the head 25 the knife 38 will be securely clamped 95 in the jig.

Fig. 16 illustrates form of jig 40 similar to the jig 36 except that it has two tongue forming knives rigidly secured therein.

It is obvious that many other forms of 100 knives may be used in the various jigs herein shown and described, but it is thought that this disclosure illustrates the invention thoroughly.

The operation of the device is very simple. The knives are first placed in the jigs, the jigs are then inserted into the recesses in the heads from one end thereof and the stud bolts screwed outwardly against the walls of recesses to securely clamp the jigs in the 110 heads and the knives in the jigs. 105

The various forms of jigs are all adapted to fit within the same heads so that any form of knife may be quickly and easily placed in the head, thus obviating the necessity of changing the entire head when a different class of work is to be done. 115

Manifestly changes in the form of construction of the various parts of this device may be resorted to without departing from 120 the spirit of the invention or sacrificing any of its advantages.

What I claim and desire to protect by Letters Patent is:—

1. The combination with a cutter head 125 having peripheral recesses extending lengthwise thereof, the rear walls of said recesses being inclined forwardly at an acute angle to the bottom walls thereof, of blade clamping jigs fitted within said recesses and pro- 130

vided with forwardly inclined blade receiving slots, said jigs having front walls at right angles to the bottom walls thereof and forwardly inclined rear walls at an acute angle to the said bottom walls thereof, toe-pieces on said jigs adjacent the bottoms thereof, and stud bolts carried by said jigs in said recesses adapted to be screwed outwardly to clamp said jigs within said cutter head recesses.

2. A device of the class described comprising a cylindrical head having peripheral recesses extending lengthwise thereof, the rear walls of said recesses being inclined forwardly at an acute angle to the bottom walls thereof, blade clamping jigs fitted within said recesses and having forwardly inclined rear walls, said blade clamping jigs having

forwardly inclined slots for the reception of blades, said slots extending through the greater part of said jigs whereby a narrow wall of metal is left at the bottoms of said slots to join the two sides of said jigs so as to permit said sides to be clamped tightly against said blades, and stud bolts carried by said jigs in said recesses adapted to be screwed outwardly to clamp said jigs within said recesses and said blades within said inclined slots of the jigs.

Signed by me at Seattle, Washington, this 14 day of June, 1917.

JOHN HEGGEN.
